UNITED STATES PATENT OFFICE.

CARL L. MANGUM, OF BIRMINGHAM, ALABAMA.

WARP CLAMP FOR LOOM BEAMS.

Application filed April 28, 1924. Serial No. 709,693.

To all whom it may concern:

Be it known that I, CARL L. MANGUM, a citizen of the United States of America, residing at Birmingham, in the county of 5 Jefferson and State of Alabama, have invented certain new and useful Improvements in Warp Clamps for Loom Beams, of which the following is a specification.

My invention relates to a warp clamp for 10 loom beams.

In present practice a considerable amount of the warp is lost when the beam is transferred to the tying-in machine, due to the fact that the warp threads do not come in 15 even condition and generally from 20" to 30" must be cut off before the tying-in operation. This is largely due to the character of the means employed for holding the warp threads in position on the filled beam.

20 The object of my invention is to design a simple and inexpensive clamp which has the novel characteristic of being formed of separable rigid elements, one of which is adapted to be applied to the beam while running 25 so that the warp threads will be drawn over it after the beam has completed a rotation. The other element is thereupon adapted to be interlocked with the first element so as to clamp all of the warp threads between rigid 30 surfaces of the assembled clamp in proper position.

A further distinctive feature of my invention is that the clamp projects beyond the ends of the beam in convenient position to 35 rest on the rails of the tying-in or drawing-in machine so as to present the warp threads in most convenient position for the tying-in operation.

My invention contemplates the utilization 40 of a clamp formed of separable sections, one of which is provided with suitable clamps adapted to engage over the ends of the warp beam, thereby permitting such clamp section to be quickly and readily applied without 45 stopping the machine which is very objectionable as it may vary the coloring of the warp threads or change its uniform characteristics, as by leaving too much sizing in that portion of the warp threads left standing in the sizing.

A further advantage of utilizing the angle members to form the clamp is that the pads can be set in the indented face of the

under clamp member and be thus protected from damage. 55

My invention also comprises the novel details of construction and arrangement of parts, which in their preferred embodiment only are illustrated in the accompanying drawings which form a part of this specification, and in which:—

Fig. 1 is a side view of a loom beam with my improved warp clamp applied.

Figs. 2 and 3 are detail views of the ends respectively of the under and upper clamp member showing the manner of attaching the several clamp springs.

Fig. 4 is an enlarged cross-sectional view through the assembled warp clamp showing the position of the warp threads when 70 clamped therein.

Fig. 5 is a longitudinal sectional view through one end of the clamp assembled.

Fig. 6 is a view of the two clamp members 75 preparatory to assembling.

Similar reference numerals refer to similar parts throughout the drawings.

I have shown my invention as applied to a typical loom beam having ends 1, to each of which is applied a gear 2 typical of a let 80 off for the beam. The warp threads 3, Fig. 4, are wound on the beam in accordance with the practice well understood in the art.

My clamp comprises a lower rigid member 4 preferably in the form of an angle iron or 85 piece of sheet metal bent transversely to stiffen it and provide it with an indented surface. At both ends of this member I mount a hold-down plate 5 under which the upper ends of heavy bent wire spring 90 arms 6 extend and are clamped in place by bolts 7, said members being brought up through slots or openings 8 provided in the angle.

The wire is bent to form two parallel legs out-turned at the lower end of the 95 loop so as to form a spring element 9 which can be forced down over the end of the beam and grip it with sufficient strength to hold the clamp member in position. Between the clamp connections at each end I 100 mount in the indented face of the clamp member 4 a pad or cushion 10. The upper clamp member 11 is also preferably in the form of a metallic angle but its shape will conform to that of the member 4. At one 105 end this member 11 is adapted to pass un-

der and be held down by the overhung end 12 of the hold-down plate 5. At its other end, the member 11 carries a spring clip 13 which is bolted thereto through a triangular shaped block 14. The sides of clip 13 are bent inwardly and then outwardly so as to spring over and clasp the sides of the clamp member 4 when the two elements of the clamp are assembled. This member 11 when 10 engaged under one hold-down end 12 will at its other end 12 fall just short of the other hold-down end 12. The clamp at both ends projects substantially beyond the ends of the beam sufficiently to engage and ride 15 on the rails of the tying-in machine.

In operation, when the loom beam has been filled and it is ready to clamp the warp, the operator first applies the clamp member 4 to the running beam, this being an easy 20 operation as it is only necessary to drop the clamp member over the warp threads and press it down so that its springs 9 will engage over and clamp the marginal portions of the beam heads. After the beam has 25 made a complete rotation the warp threads will be laid over the clamp member 4 and then the outer clamp member 11 is applied by slipping one end under the hold-down 30 12 and pressing its other end with its spring clamp 13 down to interlock it with the member 4. The clamp is thus assembled and the machine can be stopped and the loom beam removed, after which the warp threads are cut straight across about four inches 35 from the clamp. Obviously the threads being gripped between the rigid angle members 4 and 11 will be firmly and positively held in true alignment across the beam and there will be no slippage during the storage 40 or transfer of the beam and there will be no necessity for loss of more than enough of the warp to accomplish the tying-in operation. My device will thus effect a very 45 large saving in waste of warp thread over the present prevailing practice.

It is obviously desirable that the clamps 9 shall engage the marginal portion of the ends or beam heads as, when so engaged, the inner clamp member is free to rotate with 50 the beam and the clamp is most easily applied. When I refer to the marginal portion of the beam heads I mean any portion thereof where the attachment of the clamp will not interfere with the bearings or any 55 other part of the slasher as the inner clamp member rotates with the warp beam.

Though I have described with great particularity the details of the embodiment of the invention herein shown, it is not to be construed that I am limited thereto, as 60 changes in arrangement and substitution of equivalents may be made by those skilled in the art without departing from the invention as defined in the appended claims.

Having thus described my invention, what

I claim as new and desire to secure by Letters Patent, is:—

1. A warp clamp for loom beams, comprising a rigid inner member having means to detachably engage the marginal portion of the beam heads, a rigid outer member, and a spring clamp element adapted to detachably interlock said inner and outer clamp members and clamp the warp threads between them. 75

2. A warp clamp for loom beams, comprising a rigid inner member having means to detachably engage the marginal portion of the beam heads, and a rigid outer member carrying a spring clamp element adapted to detachably engage and interlock with said inner clamp member and clamp the warp threads between them. 80

3. A warp clamp for loom beams, comprising a rigid inner member having opposed springs spaced to clamp between them the marginal edges of the ends of the beam, and an outer member adapted to be clamped to the inner member and to hold the warp between them. 85 90

4. A warp clamp according to claim 3, in which the inner member carries at one end a hold-down for the outer member and the outer member has at one end a clamp adapted to detachably engage the inner member. 95

5. A warp clamp according to claim 3, in which the clamp members are angled in cross section and the springs are stiff elements rigidly mounted on the apex of the inner clamp member to hold its channel uppermost when in position on the beam. 100

6. A warp clamp for loom beams, comprising an inner rigid angle member having springs adapted to clamp between them the ends of the beam, a hold-down at one end of said member, an outer clamp member adapted to engage said hold-down at one end, and a spring to clasp its other end to the inner member, said members when assembled being adapted to clasp the warp threads 110 firmly between them.

7. A warp clamp according to claim 6, in which the inner member has duplicate hold-downs at its inner ends and the outer clamp member carries at one end the spring which is adapted to clasp it to the inner member. 115

8. A warp beam clamp comprising two separable clamp members, the inner member being rigid, means to detachably mount said inner member on the beam heads, said mounting means and inner clamp member being of such character as to permit the clamp member to make a complete rotation with the beam, and an outer element adapted to engage the inner member so as to clamp between them the warp threads wound over the inner member by its rotation with the beam. 120 125

In testimony whereof I affix my signature.
CARL L. MANGUM.
